TELEPHONE SYSTEM

Charles Edmund Beale, Liverpool, England, assignor to Associated Telephone & Telegraph Company, Chicago, Ill., a corporation of Delaware

Application April 5, 1937, Serial No. 134,991
In Great Britain May 18, 1936

6 Claims. (Cl. 179—7.1)

The present invention relates to telephone systems and is more particularly concerned with systems in which subscribers are charged in accordance with the length of their conversation, at any rate on calls which involve a number of exchanges. The chief object of the invention is to provide a simple and inexpensive time-metering system which can be readily incorporated in either new or existing exchange areas with a minimum of difficulty.

According to the invention in a telephone system including a plurality of exchanges and provided with arrangements for time metering the timing equipment is located at a central point and the metering equipment at the originating exchange is operated by alternating current signals transmitted over the speaking leads in series during conversation.

The invention will be better understood from the following description of one method of carrying it into effect, reference being had to the accompanying drawings comprising Figs. 1 and 2.

Fig. 1 shows sufficient of the trunking arrangements of a typical multi-office area to enable the application of the invention to be understood, only the equipment involved in outgoing calls to a distant exchange being shown. C denotes a central or so-called tandem exchange, M a main exchange, S a satellite exchange and SS a sub-satellite exchange. Fig. 2 shows the elements of the speech transmission circuit between a calling sub-satellite subscriber and the timing group TG which is interposed between the central exchange and a long junction to a distant exchange. The comparatively expensive timing groups need only be associated with those routes which merit the provision of timing facilities. Sufficient of discriminating final selector repeater DFSR is also shown to enable the operation of the metering relay resetting group MRRG enclosed in the dotted rectangle to be understood. The group MRRG may be added to existing exchange switches in any convenient manner while in new exchanges it may be incorporated on the switches concerned.

Referring now to the trunking diagram Fig. 1, an outgoing call from a sub-satellite subscriber to a distant exchange will first be described. When the subscriber removes his receiver, he is connected via the line finder LF to a discriminating final selector repeater DFSR, which causes the junction hunter JH to select an incoming discriminating selector repeater DSR at the satellite exchange S and this in turn causes its junction hunter JH to select a first code selector FCS

in the main exchange. In response to the digits dialled, discrimination takes place in the discriminating switches with the effect in this instance that the junctions to main are retained, and the discriminating switches function only as impulse repeaters thereby preventing access to subsequent local switches at either the satellite or sub-satellite exchanges. On seizure of the first code selector, a register controller hunter RCH selects an idle register controller RC which stores the digits dialled and retransmits them after translation in the well-known manner to actuate the first code selector and subsequent switches to route the call over the outgoing junction to its destination at the distant exchange. A special timing group TG is interposed between the central exchange selector repeater SR and the outgoing junction and this may give facilities for discrimination, alternating current dialling and the like in addition to time metering.

Referring now to the circuit diagram Fig. 2, it will be understood that when the called subscriber answers, the shunt field relay D in DFSR will be operated in the well-known manner and at armature *d2* it completes the starting circuit for the meter delay set. This latter piece of apparatus comprises relays DA and DB which are operated by so-called S and Z pulse cams which are arranged to supply battery pulses with a definite time relation to two corresponding leads. Upon reception of the next S pulse, relay DA will be operated over its lower winding and prepares a circuit at armature *da3* for relay DB which operates after the appropriate time interval from the Z pulse in series with the upper winding of relay DA. Relay DA remains locked over its middle winding until relay DB operates from the Z pulse while at the same time relay P in the resetting group will be operated over its left-hand winding and will lock over its right-hand winding to earth by way of armatures *p2*, *db3* and *b1*, contact *b1* being controlled by the usual slow-acting relay which is in turn controlled by the line relay A. On the operation of relay DB, both the initial energising circuit and the locking circuit for relay DA are opened but this relay remains held over its upper winding in series with the lower winding of relay DB for the duration of the Z pulse. During the application of the Z pulse the metering relay, (not shown) is impelled one or more times in known manner, according to the zone fee required, and at armature *j1* extends booster battery pulses over the P conductor to actuate the subscriber's meter MTR accordingly. At the cessation of the Z pulse, relay DA restores and pre-

vents any further operation of the metering relay, while relay DB remains operated in series with the junction switching relay K and the junction hunter magnet JHM since its upper winding is no longer short-circuited at armature db_3 . Both relays P and K remain operated in series with the upper winding of relay DB.

It will be understood that on the reply of the wanted party a timing device in the group TG 10 is set into operation. This device may conveniently take the form of a small self-starting induction synchronous motor driven off the alternating current supply used for long distance dialling purposes or the more conventional uni-directional switch stepped by earth pulses at ten-second intervals may be used.

Towards the end of the predetermined unit conversational period it is arranged that a "pip-pip-pip" warning signal at a frequency of the order of 800 cycles is returned to the calling party by way of the generator Y and condenser QB. A short interval ensues and at the end of this period a pulse of low frequency alternating current of for instance 50 cycles is sent back by way of the generator X and condenser QA in order to operate relay AC and reset the meter relays in DFSR. The latter pulse is applied for an appreciable period which is of the order of fifty milli-seconds in order to ensure that the meter relays are reset properly and it is of a low frequency so as not to cause any inconvenience to the calling subscriber. Should he not desire to continue the conversation, it is necessary for him to restore his receiver during the grace period or otherwise he will be charged for a further conversational period. Relay AC is bridged across the line at DFSR in the sub-satellite exchange by way of a suitable low-pass filter F which renders the relay responsive only to the low frequency signal pulse and reduces the speech transmission loss to a minimum. The arrangement of rectifiers MRA to MRD enables an ordinary telephone relay to respond satisfactorily to alternating current whilst the full-wave rectifier arrangement ensures maximum efficiency. Relay AC will therefore be operated for the duration of the low frequency pulse and at armature ac_1 it provides an earth to hold relays P and K and to shunt down relay DB which when it restores to normal short-circuits its own holding winding at armature db_3 . At the conclusion of the pulse, relay AC restores and relays P and K remain held from earth over armatures b_1 and db_3 while since relay D is still operated, relays DA and DB will again be operated in the same manner as before over the S and Z leads and will cause a further set of registrations to be effected on the subscriber's meter.

Preferably, during the extension of the low frequency repeat-metering pulse from the group TG, the through connection to the distant exchange will be disconnected and a holding loop will be provided to hold the distant train of switches. This ensures that all the signalling current is directed back towards the signal receiving equipment thereby maintaining the efficiency of the scheme at a maximum.

Referring again to the trunking diagram, it will be seen that a metering relay resetting group MRRG is associated with the satellite exchange discriminating selector repeaters serving local subscribers while in the main and central exchanges the first code selectors serving local subscribers are equipped likewise. Since the above mentioned switches are all equipped with similar

DA and DB relay arrangements, time metering can be effected in a precisely similar manner to that described for the sub-satellite case. It will be noticed however that with the equipment shown repeat metering will only take place on 5 calls which pass through the central exchange.

I claim:

1. In a telephone exchange system having means for extending a call from a calling subscriber's line in a local exchange to a called subscriber's line in a distant exchange by way of a central exchange and trunk lines connecting said exchanges, a message register associated with said calling line, means in said local exchange for initially operating said register a predetermined number of times when said connection is first established, means in said central exchange for transmitting alternating current to said local exchange over said trunk line upon the termination of each unit period of time during which said connection is maintained, and means in said local exchange responsive to said current for reoperating said register.

2. In a telephone exchange system having means for extending a connection from a calling subscriber in a first exchange to a called subscriber in a second exchange by way of a third exchange over a trunk line connecting said first and third exchanges, a message register associated with said calling subscriber's line, and means for operating said register a predetermined number of times for each unit period of time during which said connection is maintained, said means comprising a timing group in said third exchange adapted to periodically connect an alternating current of a particular frequency to the conductors of the trunk line in series and a metering relay group in said first exchange adapted to respond only to said particular frequency of alternating current, said particular frequency being such as not to interfere with conversation between said subscribers.

3. In a telephone system having means for extending a connection from a calling subscriber in a first exchange to a called subscriber in a second exchange by way of a third exchange over a trunk line connecting said first and third exchanges, a message register associated with said calling subscriber's line, a metering relay group in said first exchange for initially operating said register a predetermined number of times when said connection is established, and means for causing said metering relay group to operate said register a predetermined number of times for each unit period of time during which said connection is maintained, said last means comprising a timing group in said third exchange adapted to periodically connect an alternating current of a particular frequency to the conductors of the trunk line in series and means in said metering relay group adapted to respond only to said particular frequency of alternating current.

4. In a telephone system having means for extending a connection from a calling subscriber in a first exchange to a called subscriber in a second exchange by way of a third exchange over a trunk line connecting said first and third exchanges, a message register associated with said calling subscriber's line, a metering relay group in said first exchange, means in said metering relay group for initially operating said register when said connection is established, and means for causing said metering relay group to operate said register a predetermined number of times

for each unit period of time that said connection is maintained, said last means comprising a timing group in said third exchange adapted to periodically connect an alternating current of a particular frequency to the conductors of the trunk line in series, a relay in said metering relay group responsive only to said particular frequency of alternating current and normally disconnected from said trunk line, and means for connecting said relay to said trunk line responsive to the operation of said means in said metering relay group.

5. In a time metering arrangement for a telephone exchange system, a message register, a second relay, means for operating said first relay, means for operating said second relay only in case said first relay is operated, means for operating said register only while both of said relays are operated, time controlled means including a source of alternating current for deenergizing said second relay, means controlled by said second relay for deenergizing said first relay, and means for sequentially reoperating said relays.

time controlled means including a source of alternating current for short-circuiting and thereby deenergizing said second relay, and means for sequentially reoperating said relays.

6. In a time metering arrangement for telephone systems, a message register, a first relay, a second relay, means for operating said first relay, means for operating said second relay only in case said first relay is operated, means for operating said register only while both of said relays are operated, time controlled means including a source of alternating current for deenergizing said second relay, means controlled by said second relay for deenergizing said first relay, and means for sequentially reoperating said relays.

CHARLES EDMUND BEALE.
